UNITED STATES PATENT OFFICE.

FRANK E. BOCORSELSKI, OF RICHMOND, VIRGINIA.

DRILL-CHUCK.

1,131,990.

Specification of Letters Patent.

Patented Mar. 16, 1915.

Application filed May 16, 1914. Serial No. 339,061.

To all whom it may concern:

Be it known that I, FRANK E. BOCORSELSKI, a citizen of the United States, and residing at Richmond, in the county of Henrico and State of Virginia, have invented certain new and useful Improvements in Drill-Chucks, of which the following is a specification.

This invention relates to drill-chucks, and 10 its primary object is to provide a chuck or bit-holder so constructed as to engage a grooved drill-bit at diametrically-opposite points within its spiral groove.

A further object of the invention is to 15 provide a bit-holder with oppositely-disposed clamping-arms provided with fingers adapted to engage a drill-bit at diametrically-opposite points, said fingers extending into the grooves of the bit and to clamp the 20 bit without tapering the drill-head and without requiring the tapered sleeve usually employed to secure the shank of a twist-drill bit to its head.

A still further object of the invention is, 25 to provide a bit-holder or chuck so constructed as to permit a twist-drill bit to be inserted into or withdrawn from, its holder or chuck by a rotary movement of the bit, thus especially adapting the improved 30 holder for use in connection with a reversible shankless bit.

With this brief outline of the main objects of the present invention, the same will now be specifically described in connection 35 with the accompanying drawing which constitutes a part of this specification; and its elements of novelty and distinguishing features over the prior art will be set forth and defined in the appended claim.

40 In the drawing: Figure 1 is a central longitudinal section of one embodiment of the invention, the drill bit being illustrated by dotted lines. Fig. 2 is an end elevation of the bit-holder and bit, the latter being shown in transverse section. Fig. 3 is a section taken on the line 3-3 of Fig. 1, illustrating one means for pivotally securing the fingers of the bit-holder to the drill head, Fig. 4 is an end elevation similar to Fig. 2 45 showing bit-engaging fingers 4 of slightly modified form. Fig. 5 is a central longitudinal section of a modified construction of chuck or drill-holder embodying the invention. Fig. 6 is an end elevation of the same, and, Fig. 7 is an elevation of the flat 50 ring shown in Figs. 5 and 6 detached from the chuck.

The reference numeral 10 designates the hollow cylindrical head of the bit-holder or chuck having external threads 11 at one end 60 for the engagement thereon of a clamping sleeve 12 formed with internal screw threads 13. The head 10 is channeled or recessed at diametrically-opposite points to provide a pair of parallel shoulders 14 at each side of 65 the head between which are pivotally secured two clamping arms 15, the free ends of which are each formed with a rounded finger 16, said fingers being transversely-aligned and projecting toward each other to 70 project into the grooves 17 of a shankless reversible bit 18 and tightly engage the body of the bit within the grooves, at diametrically-opposite points as clearly shown in 75 Figs. 1, 2, and 4.

As best shown in Fig. 3, the parallel shoulders 14 of the head 10 are formed with aligned openings to receive pivot-supports 19 which secure the arms to the head, said arms each having a perforation registering with 80 the openings in the shoulders. This pivotal support for the arms may be a screw as shown in Fig. 3, or any equivalent securing device might be employed. The outer sides 20 of the arms 15 are preferably slightly inclined to coact with the rounded edge 21 of an annular flange 22 projecting inward from one end of the sleeve 12, the opposite end of which is milled or corrugated as at 85 23 to facilitate the turning of the sleeve to 90 tightly clamp the fingers 16 upon the bit, or to loosen the fingers to permit of the easy withdrawal of the bit. The drill head 10 is provided with any suitable shank or spindle projection 24 at its unthreaded end for attachment to any suitable rotating means, 95 not shown; and is also provided in addition to a bit-receiving bore 25, with a cylindrical chamber 26 communicating with and constituting a diametrically-reduced extension of 100 the bore 25, and forming an annular shoulder 27 within the drill head.

The utility and operation of the improved bit-holder constructed as above described, will be readily understood by those 105 skilled in the art to which the invention relates. When the sleeve 12 is turned to loosen the clamping arms sufficiently, one end of a shankless reversible bit, pointed at both ends, is inserted between the fingers 110

16, and is then turned and thus fed into the bore of the hollow head 10 of the drill until the inner end of the bit is seated against the shoulder 27. The sleeve 12 is then 5 turned in the opposite direction to firmly clamp the fingers 16 on opposite sides of the bit within its grooves at diametrically opposite points, thus firmly holding the bit within the drill head to rotate therewith.

10 In the form of the device shown in Fig. 4, the bit 18^a is shown on a slightly larger scale, the grooves 17^a are of different and flatter contour than the corresponding parts in Fig. 2; and the fingers 16^a are flattened 15 more than the finger 16 of Fig. 2. Otherwise this modified construction is identical with that shown in the other figures of the drawing.

Referring now to Figs. 5, 6, and 7 of the 20 drawing, the numeral 10^a designates the chuck-head, and 15^a the clamping arms thereof pivotally-secured within the head as already described in connection with Figs. 1 to 4. The sleeve 12^a instead of being 25 provided with the interior end flange 22 as in Fig. 1, is formed with an annular shoulder against which fits a clamping ring 28 rounded on its inner surface as at 30 to bear upon the free ends of the arms 15^a, and 30 formed with diametrically opposite lugs 31 fitting in slots of the head 10^a. An externally-threaded flat ring 29 engages internal threads of the sleeve 12^a to hold the clamping ring in position.

35 It will be noted that the improved bit-holder is especially well adapted to receive a reversible, shankless bit but contemplates and includes broadly, a bit-holder having

diametrically opposite clamping devices 40 adapted to engage a twist-drill at diametrically opposite points within the grooves of the drill-bit, and thus maintain the bit firmly within the drill head, said head and bit to be rotated together by any means or devices which will effect the necessary 45 rotary motion.

A reversible bit formed without a shank, and especially designed for use with the present invention, constitutes the subject-matter of another application filed by me, 50 May 16, 1914, Serial No. 839062.

I would have it understood that the invention is not restricted to the details of construction except as hereinafter claimed, but includes all such modifications and 55 variations in structural details as may fall within the scope and terms of the claim.

What I claim as new is:—

A drill chuck embodying an externally threaded head provided at its outer end 60 with two pairs of transversely aligned spaced shoulders, a pair of jaws having their inner ends pivoted between the shoulders, and their outer ends terminating in inward projecting oppositely aligned terminally rounded fingers, and a sleeve threaded on the head and furnished at its outer end with an inward projecting transversely rounded annular flange to engage the jaws.

In testimony whereof I affix my signature 70 in presence of two witnesses.

FRANK E. BOCORSELSKI.
